UNITED STATES PATENT OFFICE.

HARTWELL L. EDRIDGE, OF MINNEAPOLIS, MINNESOTA.

GAS GENERATOR AND BURNER.

Application filed January 23, 1922. Serial No. 531,051.

To all whom it may concern:

Be it known that I, HARTWELL L. EDRIDGE, a citizen of the United States, residing at Minneapolis, in the county of Hennepin and 5 State of Minnesota, have invented certain new and useful Improvements in Gas Generators and Burners; and I do hereby declare the following to be a full, clear, and exact description of the invention, such as will 10 enable others skilled in the art to which it appertains to make and use the same.

My invention has for its object to provide a simple and highly efficient gas generator and burner adapted for the burning of 15 heavy hydro-carbon, such as kerosene, distillate and crude oil, and to such ends, generally stated, the invention consists of the novel devices and combinations of devices hereinafter described and defined in the 20 claims. In one commercial form, the combined generator and burner is applied to, supported by and removable with one of the lids of a range, cooking stove or other stove having one or more lids, but the general 25 construction illustrated is capable of a wide range of use and may, for illustration, be also used in ordinary heating stoves and furnaces or boilers.

In the accompanying drawings, which illustrate the invention, like characters indicate like parts throughout the several views.

Referring to the drawings:

Fig. 1 is a view partly in side elevation 35 and partly in vertical section illustrating the invention as applied to one of the lids of an ordinary range or cooking stove;

Fig. 2 is a transverse vertical section taken on the line 2—2 of Fig. 1;

Fig. 3 is a plan view of the combined generator and burner with the hood thereof removed; and

Fig. 4 is a bottom plan view of the parts shown in Fig. 3.

Of the parts of the range or stove, the 45 numeral 5 indicates the top plate, the numeral 6 the fire box, the numeral 7 the grate and the numeral 8 one of the removable lids, which latter is of special design, being preferably constructed as follows: Said lid is provided with an upstanding marginal flange 9, just inward of said flange with an annular channel 10, just inward of said channel with an upstanding annular vaporizing chamber 11, and, at its axis or center,

with a flanged neck 12 that affords a central passage. Between the central passage 12 and vaporizing chamber 11, the lid 8 is formed with circumferentially spaced air ports 13.

Mounted on the flange of the neck or central passage 12 is an oscillatory valve 14 of the damper type, but which is provided with a central passage 15 that always remains open, regardless of adjustments of said valve or damper.

The hydro-carbon liquid will be supplied to the vaporizing chamber 11 through a supply pipe 16 that leads from a source of supply such as an elevated tank, not shown. Extending radially inward from the vaporizing chamber 11 is a vapor delivery pipe 17 that terminates in a depending vapor discharge nozzle 18 located immediately over the central passage 15. This nozzle 18 is arranged to be opened and closed to any desired extent by a needle valve 19, the stem of which projects upward and, as shown, is provided at its upper end with a centrally pivoted hand piece 20.

The numeral 21 indicates a hood that entirely covers the lid and is preferably formed from sheet metal having a depending marginal flange 22, the lower edge of which is detachably seated in an annular channel 85 formed on the upper edge of the lid flange 9. Near its lower end, the hood flange 22 is provided with small circumferentially spaced air intake ports 23. At one side, said flange 22 has a notch 24 that adapts the lid to be set over the horizontal portion of the fuel supply pipe 16. At its center, the hood 21 has an axial passage through which the stem of the needle valve 19 is passed. When the hand piece 20 is turned into alignment with the valve 19, the hood 21 may be removed from or applied to the stem of said needle valve. Surrounding its central point, the hood 21 is formed with large auxiliary air intake ports 25 that are adapted to be opened and closed to any desired extent by an oscillatory damper or valve 26.

Secured to and depending from the lid 8 and aligned with the neck or central passage 12 thereof is a perforated conical shell 105 27, and secured to said lid and depending therefrom is an imperforate cylindrical outer shell 28, the lower edge of which is united to the lower edge of the conical shell 27. The numeral 29 indicates an air tube 110

that is secured to the lower edges of the shells 27 and 28 and is extended diametrically thereof and, at its outer end, has upturned extensions 30 that open through the 5 sides of the shell 28 at diametrically opposite points. At its central portion, the tube 29 has a short upwardly extended stack 31 located on the axis of the conical shell 27.

The numeral 32 indicates a perforated inner conical shell located concentric to and within the shell 27 but spaced therefrom, and from the upper end of the stack 31. The apex of this inner shell 32 is aligned with and located just below the constantly 10 open central passage 15. The lower end or base of said conical shell 32 is closed by a disk-like plate 33.

The operation of this combined generator and burner is substantially as follows:

20 To start the burner into action, a small amount of gasoline will be placed in the annular channel 10 of the lid and is ignited. The gasoline can be readily placed in said channel 10 when the hood 21 is slightly raised, 25 or it might be squirted into said channel from an oil can through one of the ports 23. The initial heat produced by the burning of this gasoline will convert the hydro-carbon fuel contained within the vaporizing 30 chamber 11 into gas or vapor form, and when the valve 19 is open, the discharge of gas or vapor from the nozzle 18, under the action of the constant downward draft from the stove, will be through the passage 15 into 35 the space between the perforated shells 27 and 32. The draft from the stove will draw air through the ports 23 and 25 into the hood and from thence downward through the air ports 13 and also through the openings of the valve 14 if, in fact, the latter be open. Part of the hydro-carbon vapor primarily drawn into the space between the perforated shells 27 and 32 will be drawn outward through the shell 27, part thereof will 40 enter the inner shell 32 and part thereof will be drawn directly downward through the two near semi-circular openings formed on opposite sides of the tube 29 at the lower extremities of said shells 27 and 32. Part 45 of the air drawn into the space between the shells 27 and 28 will be drawn into the annular space between said shells 27 and 32 and will be immediately commingled with the hydro-carbon vapor, but a considerable 50 part of the air will be drawn through the tubes 30, 29 and 31 into the interior of the inner perforated shell 32, where it will be commingled with more or less vapor or gas and from whence it will be drawn with the 55 vapor into the space between the shells 27 and 32 and discharge downward at the bottom openings formed between said shells. Thus, it will be seen that in several different ways, the hydro-carbon vapor and air are 60 commingled and, hence, will be burned in 65

the most efficient possible manner, within the fire box of the stove. Of course, as soon as the generation of the hydro-carbon vapor in the chamber 11 is once established, the heat conducted through the metallic parts 70 to the lid and to the metal walls of said chamber 11 will be sufficient to maintain such vaporization or generation of the hydro-carbon gas or vapor.

The intensity of the flame may be regulated by varying the adjustments of the needle valve 19 to give the proper supply of hydro-carbon vapor, but different adjustments of said needle valve will require varying regulation of the air supply and this 80 may be taken care of by adjustments of the damper-acting valves 26 and 14.

In actual practice, the efficiency of this gas generator and burner has been thoroughly demonstrated. Not only is the device highly efficient, but it may be produced at small manufacturing cost. When applied to the lid of a stove, it may be quickly and easily removed, if at any time it should be necessary or desirable to use wood or coal 90 in the stove.

What I claim is:

1. A gas generator and burner comprising a supporting plate having air ports, inner and outer perforated conical shells supported below said plate, a nozzle above said plate arranged for the delivery of fluid fuel into the space between said conical shells, a shell surrounding said perforated shells, and an air duct extending from the side of 100 said latter noted shell into the interior of said inner perforated conical shell.

2. A gas generator and burner comprising a supporting plate having air ports, inner and outer perforated conical shells supported below said plate, a nozzle above said plate arranged for the delivery of fluid fuel into the space between said conical shells, a shell surrounding said perforated shells, and air ducts extending from the opposite sides 110 of said latter noted shell and having a stack 105 extended into said inner perforated conical shell.

3. The structure defined in claim 1 in which there is an air damper located between said nozzle and the upper extremities 115 of said perforated conical shells.

4. The structure defined in claim 2 in which there is an air damper located between said nozzle and the upper extremities 120 of said perforated conical shells.

5. The structure defined in claim 1 in further combination with a hood overlying said supporting plate, a vaporizing chamber between said hood and plate and to which 125 said nozzle is connected, and means for supplying fluid fuel to said vaporizing chamber.

6. The structure defined in claim 5 in which said hood is provided with constantly 130

open and with damper-controlled auxiliary air intake ports.

7. The structure defined in claim 5 in which said plate is provided with a damper-controlled air passage between said nozzle and the upper extremities of said perforated conical shells.

8. The structure defined in claim 5 in which said plate inward of said hood is provided with an annular channel adapted to receive a starting charge of gasoline or the like.

9. The structure defined in claim 5 in which said nozzle has a valve, the stem of

which projects above said hood, said hood being movable vertically thereon.

10. The structure defined in claim 1 in which said supporting plate is in the form of a stove lid, the entire device including said lid constituting a self-contained portable structure.

11. The structure defined in claim 5 in which said supporting plate is in the form of a stove lid, the entire device including said lid constituting a self-contained portable structure.

In testimony whereof I affix my signature.
HARTWELL L. ED RIDGE.
